UNITED STATES PATENT OFFICE.

CHARLES F. SCATTERGOOD, OF ALBANY, NEW YORK.

DESIGN FOR A DIAL FOR ELECTRICAL ANNUNCIATORS.

SPECIFICATION forming part of Design No. 23,112, dated March 13, 1894.

Application filed December 28, 1893. Serial No. 495,008. Term of patent 7 years.

To all whom it may concern:

Be it known that I, CHARLES F. SCATTERGOOD, a citizen of the United States of America, residing at Albany, Albany county, New York, have invented and produced a new and original Design for an Electrical Announcer-Dial; and I do declare the following to be a full, clear, and exact description of the same, reference being had to the accompanying drawing, forming a part thereof.

The figure shows a front elevation of my design.

My design relates to a new and original ornamental surface for the announcer dial of an electrical announcer, and consists of a

rectangular plate or dial ornamented by a series of circular openings disposed in a circle thereon and by a series of lines of circular openings within the circle of openings, forming an ornamental dial to said announcer.

What I claim is—

The design for the dial of an electrical announcer herein shown and described.

In testimony whereof I affix my signature in presence of two witnesses.

CHARLES F. SCATTERGOOD.
